CLAIM

The ornamental design for a tape cartridge for tape printer, as shown and described.

DESCRIPTION

FIG. 1 is a top plan view of a tape cartridge for tape printer; FIG. 2 is a bottom plan view of FIG. 1; FIG. 3 is a front view of FIG. 1; FIG. 4 is a rear view of FIG. 1; FIG. 5 is a left side view of FIG. 1; FIG. 6 is a right side view of FIG. 1; and, FIG. 7 is a perspective view of FIG. 1.

The tape in FIGS. 3-5 and 7 is solid black. The other solid black areas in FIGS. 1-5 and 7 are due to shadows produced during photography. It should also be understood that there is no ornamentation on the interior surfaces.
